UNITED STATES PATENT OFFICE

HARRY J. TAYLOR, OF NEW YORK, N. Y.

BREAD PACKAGE

Original application filed June 24, 1931, Serial No. 546,621, now Patent No. 1,818,923. Divided and this application filed August 8, 1931. Serial No. 555,897.

This invention relates to improvements in packaged articles and more particularly to bakers' products as wrapped for distribution.

It is a desirable thing in connection with 5 such products to impress on the minds of purchasers, other articles produced by the same manufacturers, this being usually accomplished by printing advertising matter directly on the wrapper, or by inserting a loose 10 separate sheet in the package bearing an announcement of the allied goods.

It is quite usual, however, that such wrappers and loose enclosures are removed and thrown away when the goods are to be used, 15 with little or no attention being given the subject matter displayed; hence their advertising value is practically negligible. My experience has shown that the advertising value of advertising matter distributed to purchasers 20 of bakers' products is greatly enhanced as compared with the methods above mentioned if it is applied to a band or strip affixed to the wrapper in such a way that it is not easily detached and consequently overlooked by the 25 person handling or unwrapping the product, and at the same time a contrast is established, either through coloring or otherwise, between the printed matter on the wrapper and the 30 printed matter and other attention-arresting indicia on the band or strip.

In order to comply with the requirements 35 of the trade, it is essential that this band shall be applied to the product and affixed to the wrapper without interfering with the sealing of the wrapper, and for economic reasons the production of the improved package must be effected with a minimum of additional manipulation and labor.

After extensive experimentation I have 40 developed an improved package wherein a band bearing any suitable advertising legend is so associated with the usual wrapper, either inside or outside thereof, as to encircle the loaf or other article, and is securely 45 affixed to the wrapper and contributes to the sealing of the finished package.

This improved package has the further 50 advantage that it may be formed by the use of any of the more commonly used bread

wrapping machines and without introducing an additional mechanical operation.

For a more detailed description of the invention, reference is made to the appended drawings, in which:

Fig. 1 is a perspective view of a conventional bread loaf as enclosed in a wrapper, 55 and a band displayed thereover.

Fig. 2 is an enlarged cross sectional view 60 of the same taken through the wrapper and band.

Fig. 3 is a similar view to Fig. 1, but showing the band disposed under the wrapper.

Fig. 4 is a cross sectional view of the same.

In the several figures, a conventional loaf 65 of bread is designated by the numeral 10, completely enclosed in a wrapper 11.

The wrapper is ordinarily made of strong white paper, e. g. 22# wrapping stock, impregnated with a wax, such as paraffin, colorless, odorless, moisture, oil and dirt proof, rendering the paper translucent, and, due to the wax, easily adherent upon the application 70 of moderate heat and pressure.

Such wrappers are customarily applied in 75 a machine designed specifically for this purpose and not a part of the invention. Such a machine with the necessary additional means for supplying band material in the wrapping operation is shown in my copend-

ing application Serial No. 546,621, filed June 24, 1931, now Patent 1,818,923, of which this 80 is a division. The machine carries a suitable heating means, for example, an electrically heated plate, which at the end of the 85 wrapping operation is caused to press against the overlapped edges of the wrapper so as to produce softening of the wax coating and thus effect sealing.

According to my invention a relatively narrow band 12 carrying suitable advertising matter is applied around the loaf simultaneously with the application of the wrapper so that, irrespective of whether the band is disposed inside or outside of the wrapper, the ends of the 90 band will be in overlapped relation as respects one another and in interleaved relation with the adjacent overlapped edge portions of the wrapper.

The width of the band may be varied over 95 100

a considerable range as desired, but in order to establish a greater contrast between the advertising matter on the band and the printed matter on the wrapper and thus obtain more advertising value from the band, it is preferable that it shall be relatively narrow as compared with the width or length of the loaf as the case may be. Under some conditions, as, for example, when the packaging is being effected with a wrapping machine which has become worn in service, it is important that the band shall be of greater strength per unit of sectional area than the wrapper in order to avoid tearing in the wrapping and banding operation. This greater strength may be provided by appropriate choice of material or by using material of similar quality but of greater thickness. Ordinarily, satisfactory results are obtained when the thickness, or rather the strength per unit of sectional area, is approximately twenty-five to forty per cent greater than that of the wrapper. In general, the strength of the band per unit of sectional area should be increased with decrease in width and the band should not ordinarily be less than one inch wide.

When proper precautions are taken, the band does not interfere in any way with the sealing of the wrapper but, on the contrary, contributes its part in producing a perfectly sealed package. The banding material is waxed or paraffined in a similar way as the wrapper, and, consequently, when it is fed through the machine with the wrapper to the wrapping station, severed from the strip and caused in the wrapping operation to encircle the loaf, its ends are overlapped and brought into interleaved relation with the overlapped portions of the wrapper as illustrated in Figs. 2 and 4. In this way the overlapped ends of the band are subjected to the same heating influences as are the overlapped edges of the wrapper at the proper stage in the operation, and the sealing of the band takes place simultaneously with the sealing of the wrapper. Because of the interleaved relation above mentioned, the band is affixed to the wrapper and is prevented from becoming displaced. The waxing of the band material not only makes for simultaneous sealing of the band and the wrapper in an integral seal and affixing of the band to the wrapper, but also imparts a certain stiffness to the band material which facilitates its manipulation during the wrapping and banding operation. In some cases, as for example when the packaging is being effected with a wrapping machine that has become somewhat worn in service or where the mechanical operations require that the paper being fed and manipulated shall have a certain stiffness, it is desirable to impregnate the banding material with a greater quantity of wax per unit of surface than is

carried by the wrapping paper. Ordinarily, these special conditions will be taken care of when the banding paper is impregnated with at least 30% more paraffin than is carried by the wrapping paper.

From the foregoing it will be seen that the label carrying band may be disposed either within or upon the wrapper and that no extra mechanism, other than that noted, is required, while the work is entirely automatically performed.

Although the improvements have been described with considerable detail and with respect to certain particular forms of the invention, it is not desired to be limited to such details since various changes and modifications may well be made without departing from the spirit and scope of the invention in its broadest aspect.

While the invention has been described with particular reference to the use of paper as the wrapping and banding materials, it will be understood that a fabric or other materials capable of being impregnated with paraffin and manipulated in the manner described may be employed. It is to be further understood that the terms "bread" and "loaf" as used in the claims are to be construed as including cake and similar bakers' products which are wrapped mechanically before distribution to consumers.

Having thus described the invention, what is claimed as new and desired to secure by Letters Patent, is:

1. As an improved article of manufacture the bread package hereindescribed, comprising a wrapper of waxed paper enveloping a loaf of bread, a narrow band of legend-bearing waxed paper encircling said loaf, said wrapper and said band being so associated that the ends of said band are in overlapping relation to one another adjacent an overlap of said wrapper and in interleaved and integrally sealed relation with the overlapped portions of the wrapper.

2. As an improved article of manufacture the bread package hereindescribed, comprising a wrapper of waxed paper enveloping a loaf of bread, a narrow band of legend-bearing waxed paper encircling said loaf and said wrapper, said wrapper and said band being so associated that the ends of said band are in overlapping relation to one another adjacent an overlap of said wrapper and in interleaved and integrally sealed relation with the overlapped portions of the wrapper.

3. As an improved article of manufacture the bread package hereindescribed, comprising a wrapper of waxed paper enveloping a loaf of bread, a narrow band of legend-bearing waxed paper encircling said loaf and having a tensile strength per unit of width from 25 to 45% greater than said wrapper and carrying at least 30% more paraffin per

unit of surface than said wrapper, said wrapper and said band being so associated that the ends of said band are in overlapping relation to one another adjacent an overlap 5 of said wrapper and in interleaved and integrally sealed relation with the overlapped portions of the wrapper.

In testimony whereof, I have signed my name to this specification this 6th day of 10 August, 1931.

HARRY J. TAYLOR.
